UNITED STATES PATENT OFFICE.

TRUMAN H. BENSON, OF ELLIOTT, ILLINOIS.

ATTACHMENT FOR AUTOMOBILES.

1,287,620.

Specification of Letters Patent. Patented Dec. 17, 1918.

Application filed July 6, 1918. Serial No. 243,506.

To all whom it may concern:

Be it known that I, TRUMAN H. BENSON, a citizen of the United States, residing at Elliott, in the county of Ford and State of Illinois, have invented certain new and useful Improvements in Attachments for Automobiles, of which the following is a specification, reference being had to the accompanying drawings.

10 This invention relates to an improved attachment for automobiles, and has for its primary object to provide means which may be easily and quickly attached to the wheel of an automobile, whereby the machine may 15 be pulled by its own power from sand or mud in which it has become stalled.

It is another and more particular object of my invention to provide a device for the above purpose consisting of a drum having 20 an end section provided with means for attachment to the wheel, a body section insertible over the wheel hub, and means for detachably and rigidly connecting the body section of the drum to said end section.

25 It is also an additional object of my invention to provide a device for the above purpose which may be applied to the ordinary motor vehicle wheel without necessitating any structural changes therein, and 30 which is exceedingly strong and durable and capable of manufacture at relatively small cost.

With the above and other objects in view, 35 the invention consists in the improved combination, construction and relative arrangement of the several parts as will be herein-after more fully described, subsequently claimed and illustrated in the accompanying drawing in which similar reference characters designate corresponding parts throughout the several views, and wherein:—

Figure 1 is a fragmentary perspective view of a motor vehicle wheel showing my improved attachment applied thereto:

45 Fig. 2 is a longitudinal section; and

Fig. 3 is a section taken on the line 3—3 of Fig. 2.

Referring in detail to the drawing, H designates the hub and S the spokes of a motor 50 vehicle wheel. The attachment which constitutes the subject matter of the present invention consists of a drum having an end section designated generally by the numeral 5, said drum section being formed with an 55 outwardly projecting annular flange 6, and

spaced radially disposed arms 7, which are preferably curved laterally from one face of this flange to extend over the inner enlarged end of the wheel hub. Each of the arms 7 is provided in its end with a slot or 60 opening 8 which is adapted to receive the end of a clamping bolt 9. This bolt at its opposite end terminates in a hook 10, which is adapted to extend around the inner side of one of the wheel spokes. A nut 11 is 65 threaded upon the first named end of said bolt for clamping engagement against the end of the arm 7. The tubular portion of the drum section 5 is formed with spaced bolt holes 12 extending longitudinally there- 70 through, for a purpose to be presently stated.

The body section 13 of the drum, which may be of any preferred length, is of tubular form to fit loosely over the wheel hub and is provided upon one of its ends with an 75 outwardly projecting annular flange 14. The wall of this body section of the drum is likewise provided with spaced longitudinally extending openings 15 therethrough, which are adapted to register with the openings 12 80 in the drum section 5. Connecting bolts 16 are then inserted through said openings, suitable nuts 17 being threaded upon the ends of the bolts against the end of the body section 13. In this manner, the drum body may 85 be rigidly and securely clamped upon the end section 5. The flange 6 of the end section of the drum has an opening formed therethrough adjacent the body wall of said drum section to receive an open eye or hook 90 18, to which one end of a pulling cable, indicated at 19, is adapted to be connected. The other end of the cable is tied or otherwise secured to a stake 20, which is driven into the ground at a suitable point in advance of the stalled machine. 95

From the above description, taken in connection with the accompanying drawing, the purpose and manner of operation of the device will be clearly understood. When the 100 attachment is applied, as seen in Fig. 1, and the end of the cable securely staked to the ground, the motor of the vehicle is started in operation. The driving wheels will thus be rotated, and the cable 19 will be wound upon the drum body 13 attached to one of said wheels. As the cable is thus wound upon the drum, the machine is caused to advance and is thus extricated from the sand or mud in which it has become stalled. The attach- 110

ment can then be readily removed from the wheel by simply disengaging the bolts 9 from the wheel spokes, and the sections of the drum can then be separated and the entire device packed or stored away in a relatively small space. If desired, however, the end section 5 of the drum may remain attached to the wheel, and the body section detached from said end section by removing the bolts 16. It will thus be seen that I have devised a very simple and serviceable attachment as an accessory for motor vehicles which may be very easily and quickly applied to or removed from the wheel of the ordinary automobile. The drum may be of any desired length or diameter, and while I have indicated in the drawing a particular number and arrangement of the attaching arms 7, it will be apparent that this feature, as well as the several other detail parts of the device, might be considerably varied. It is therefore to be understood that in practice I reserve the privilege of adopting all such alternative constructions as may be

fairly embodied within the spirit and scope 25 of the invention as claimed.

I claim:—

An attachment for motor vehicle wheels comprising a drum having a short end section and a relatively long body section, each 30 of said sections having an outwardly projecting flange formed on one end, means for connecting said drum sections to each other with their walls in longitudinal alinement and the connected drum sections being adapted 35 to be fitted over the hub of the vehicle wheel, a plurality of radially extending, angularly off-set arms projecting from the flange on the end section of the drum to space said flange from the spokes of the vehicle wheel, and means for clamping said arms at their extremities to the wheel spokes. 40

In testimony whereof I hereunto affix my signature in the presence of two witnesses.

TRUMAN H. BENSON.
